ATTORNEY

UNITED STATES PATENT OFFICE.

JOHN HUTZELMAN AND IGNACIO BERESFORD, OF WARNER SPRINGS, CALIFORNIA;
SAID BERESFORD ASSIGNOR TO SAID HUTZELMAN.

FUNNEL.

1,266,019.

Specification of Letters Patent.

Patented May 14, 1918.

Application filed November 1, 1915. Serial No. 59,129.

To all whom it may concern:

Be it known that we, JOHN HUTZELMAN and IGNACIO BERESFORD, citizens of the United States, residing at Warner Springs, 5 in the county of San Diego and State of California, have invented certain new and useful Improvements in Funnels, of which the following is a specification.

An object of our invention is to provide 10 a new and improved funnel which includes means to actuate the closure valve at the time the fluid in a container, in connection with which the funnel is being used, reaches a desired height, and improved means for 15 moving the closure valve to an open position when such is desired.

Another object of our invention is to provide 20 a funnel which includes means for retaining the closure valve in an open position which is designed to prevent the accidental displacement of the valve, under ordinary circumstances, and thus assure the uniform distribution of the contents of the funnel to a container.

25 A further object of our invention is to provide a new and improved funnel, wherein the means for actuating the closure valve is adjustable in a manner that may permit the operator to so position the same that the actuation of the closure valve may be controlled accordingly.

A still further object of our invention is 30 to provide a device of the type in question that is extremely simple in construction, strong and durable and highly practical from both the standpoint of the manufacturer and the standpoint of the user; and which, it is believed, may be manufactured at a minimum cost.

40 Various other objects and advantages will become apparent during the continuance of the following description.

The above and other objects which will 45 become apparent, are accomplished by such means as are shown in their preferred form in the accompanying drawings, described in the following specification, and then more specifically pointed out in the appended claim.

50 In the accompanying drawing wherein like characters designate like parts through the several views:

Figure 1 is a view in vertical section showing our invention in its preferred embodiment;

Fig. 2 is a view in cross section taken on a line slightly above the closure valve;

Fig. 3 is a view in cross section taken on line 3—3 of Fig. 1;

Fig. 4 is a view in side elevation showing 60 means for actuating the closure valve, the float being shown in section, and

Fig. 5 is a detail view of the float.

In the drawings, the numeral 10 designates the body portion of the funnel which 65 carries a mouth piece 11 at its lower end to form a funnel of substantially the conventional appearance. The outer face of the mouth piece 11 is grooved longitudinally as at 12, while a supporting plate 13 is carried 70 thereby to retain the funnel in an upright position when being used in connection with a bottle or the like container. A closure valve 14 is mounted within the body 10 of the funnel at a point slightly above the upper terminus of the mouth piece in order to adequately close the outlet passage of the funnel. This valve carries an arm 15 through the medium of brackets 16 by which it may be pivotally connected to the body 80 10 as at 17. In order to retain the closure valve normally in the closed position, spring 18 is provided that acts upon the arm 15 in the manner shown in Figs. 1 and 2. The arm 15 is also provided with an eyelet 85 19 which may be engaged by the handle 20 for moving the closure valve to an open position such as will be presently described.

A catch 21 is pivotally mounted upon the body 10 as at 22 which is designed to engage 90 the arm 15 at certain times to retain the closure valve in an open position. The body 10 carries a rod 23 which is slidably mounted through brackets 24 thereof, the upward end of this rod being bent as at 25 and being connected with the catch 21 as at 26, while its other end is bent and extends downwardly within the groove 12 of the mouth piece 11 and projects upwardly within the said mouth piece as shown at 27. The 100 bracket 28 on the body 10 pivotally supports an arm 29, the inner end of which is connected with the rod 23 as at 30, while a weight 31 is arranged upon the arm adjacent its outer end so as to normally exert the upward pressure upon the rod 23. That portion of the rod 23 which projects into the mouth piece 11 is provided with a series of teeth 32 adjacent its end, while other teeth 33 are formed adjacent the point of bending 105 110

2
 34. A float 35 is associated with this portion of the rod, the same being provided with an opening 36 for receiving the rod and pawls 37 for engagement with the teeth 5 32 and 33 to retain the same in various adjusted positions. In view of this particular construction, it will be readily recognized that the float may be adjusted longitudinally of the mouth piece 11, either higher or 10 lower in order to actuate the closure valve in the manner which will be presently described, when the fluid in the container (not shown) reaches the desired height.

In the operation of my invention, the operator 15 first adjusts the float 35 to the desired point, after which the funnel may be placed in an operative position with respect to the container. The operator then grasps the handle 20 and moves the closure valve to a 20 position whereby the arm 15 will be engaged by the catch 21 and held in an open position. As the fluid in the container reaches the desired height, the float 35 will be moved upwardly by action of the fluid which will, of course, cause the rod 23 to move in a similar 25 direction and thus withdraw the catch 21 from engagement with the arm 15. When this occurs, the closure valve will be moved by action of the spring 18 into the position 30 shown in full lines in Fig. 1 to adequately close the outlet passage of the funnel. By employing the arm 29 and the weight 31 and arranging the same in the position, the float 35 does not have to be of the usual diameter, 35 since the operation of the rod 23 is greatly aided by the weighted arm.

The teeth 33 provides means for holding the float 35 at the lower end of the vertical portion 27 of the arm 23. Provision is thus had for an extreme adjustment of the float. 40

The arm 29 provides convenient means for operating the part 23 when it is desired to release the valve 14 to admit of its closing. This arm 29 also provides for a nicety of 45 operation of the float 35 by moving the

weight 31 thereon so as to counter-balance the float 35 and the parts associated therewith. By having the weight 31 adjustable on the arm 29 resistance to the operation of the float 35 may be compensated for. 50

From the foregoing, it is believed that the advantages and novel features of our invention will be readily understood and therefore further detailed description is deemed unnecessary. 55

In reducing our invention to practice, we find that the form referred to herein is the most practical and preferred embodiment is the most efficient, but realizing that certain conditions will necessarily vary in concurrence with the adoption of our device, we desire to emphasize the fact that various minor changes in the details of construction and in the proportion of parts may be resorted to when required without sacrificing 60 any of the advantages of my invention as defined in the appended claim. 65

Having thus fully described our invention, what we claim as new and desire to secure by Letters Patent, is: 70

In combination with a funnel, a valve within the lower portion of the funnel and hinged thereto, a catch supported within the funnel for holding the valve open, a rod exterior to the funnel and having its upper end extending over and into the funnel and connected with the catch, a float at the lower end of the rod to be actuated by the liquid for automatically disengaging the catch from the valve, and a weighted arm 75 pivoted to the funnel and connected with the said rod to exert an upward pressure thereon. 80

In testimony whereof we affix our signatures in presence of two witnesses.

JOHN HUTZELMAN.
IGNACIO BERESFORD.
